WILLIAM H. COX AND THEOPHILUS LAROUCHE, OF WILLIAMSTOWN,
NEW YORK.

Letters Patent No. 96,891, dated November 16, 1869.

IMPROVEMENT IN THILL-CO尤LING.

The Schedule referred to in these Letters Patent and making part of the same.

To all whom it may concern:

Be it known that we, WILLIAM H. COX and THEOPHILUS LAROUCHE, of Williamstown, in the county of Oswego, and State of New York, have invented a new and useful Improvement in Thill-Coupling; and we do hereby declare that the following is a full, clear, and exact description thereof, which will enable others skilled in the art to make and use the same, reference being had to the accompanying drawing, forming part of this specification.

This invention relates to a new and useful improvement in device for coupling thills to buggies or other vehicles; and consists in the construction and arrangement hereinafter described.

In the accompanying sheet of drawing—

Figure 1 represents an outside view of the coupling as attached to a carriage.

Figure 2 is a vertical section of fig. 1, through the line *x x*.

Similar letters of reference indicate corresponding parts.

A is the draw-iron, which is fastened to the axle *B* by means of the clip *C*.

D is the shank, or part which is attached to the thills of the vehicle.

e is a collar on the shank, and

f is a groove in its end or journal, which enters the socket of the draw-iron.

G is the socket, which is closed at one end. The collar *e* closes the other end, so that sand and dust are excluded.

H is a screw, which passes through the socket *G*, the end of which screw enters the groove *f* in the

shank, which arrangement prevents the withdrawal of the shank, except when the thills are elevated to near a vertical position; then the slot *k* (from the end of the shank into the groove *f*) will receive the end of the screw, and allow the shank to be withdrawn.

On the screw there is a jam-nut, *i*, which, when the screw is properly adjusted, is turned tightly down on to the socket, which securely holds the screw to its place.

The shank, in attaching the thills to the carriage, is sprung into the socket by springing the thills, and it will be seen that the spring itself is sufficient to keep the thills in place and to prevent rattling without the screw *H*, but we prefer to use the screw in addition, as it makes the coupling more complete.

This is a cheap and simple arrangement, not liable to break or get out of order, and perfectly sure and safe in its operation.

Having thus described our invention,

We claim as new, and desire to secure by Letters Patent—

1. The improved draw-iron *A*, having a chamber enclosed on all sides except the end which is covered by the cap *e*, as shown and described.

2. The combination of screw *H* and jam-nut *i* with the draw-iron, and a shank provided with the cylindrical groove *S*, arranged as set forth, to prevent "rattling."

WILLIAM H. COX.
THEOPHILUS LAROUCHE.
